PACKAGE HANDLE.

Application filed January 6, 1927. Serial No. 159,495.

The invention relates in general to detachable handles of the character which includes wire hook ends designed to be secured quickly to the binding cord of parcels so that they may be conveniently carried from place to place.

Such handles heretofore constructed have usually been made of wood or metal, generally of cylindrical form and in either case requiring a certain amount of machining, and a material amount of labor in constructing the same, all of which has rendered such articles too expensive to meet present market demands for an extremely cheap article.

The primary object of the invention is to provide a simple form of package carrier which will have all the advantages, in so far as rigidity and lightness of weight is concerned, as characterizes present forms of such devices and at the same time to provide a cheaper construction than is known at present and which would not necessitate any material amount of machining or labor in its construction.

Broadly, the invention contemplates the forming of the handle of scrap pieces of cardboard or other sheet material which need not necessarily have the requisite degree of rigidity and designing the usual hook end wire to function as a reinforcement to the handle and coat therewith to provide the requisite rigidity in addition to its usual function of providing hook ends.

Another object of the invention is to provide a form of package carrier the sides of the handle portion of which can be designed so as to have advertising or other matter printed thereon prior to bending the handle forming material to shape.

Various other objects and advantages of the invention will be in part obvious from an inspection of the accompanying drawings and in part will be more fully set forth in the following particular description of one form of device embodying the invention, and the invention also consists in certain new and novel features of construction and combination of parts hereinafter set forth and claimed.

In the accompanying drawing:

Fig. 1 is a perspective view showing a preferred embodiment of the invention;

Fig. 2 is a vertical sectional view taken axially and longitudinally through the show-

ing in Fig. 1 and taken on the line 2—2 of Fig. 3;

Fig. 3 is a view in end elevation of the structure shown in Figs. 1 and 2 looking at the same from the plane indicated by the line 3—3 of Fig. 2; and

Fig. 4 is a perspective view of the end portion of a modified form of holder.

In the form of the invention shown in Figs. 1—3, there is disclosed a handle portion 10 through which extends a single length of wire 11 terminating in hook ends 12 and in general resembling conventional forms of such structures. The handle portion 10 is formed from a rectangular blank, or strip comprising one or more layers of cardboard 7th preferably of the corrugated type shown in Fig. 3. This corrugated cardboard form of handle is cut from scraps of cardboard which at present can be purchased cheaply from box factories and other plants using 7th this type of cardboard. This scrap material comes flat and has both sides defined by paper surfaces 13 and 14 which are sufficiently smooth to form an easily retained grip when shaped into the form of the 8th handle.

It is proposed to use one or both upstanding sides of the handle to accommodate advertising matter and this printed matter can be most conveniently added to the handle 8th while in the flat blank form and before it is formed into the handle. The advertisements may be printed directly thereon as shown at 15 in Fig. 4 or may be on a paper label 16 as shown in Fig. 1 and the label 9th secured as by gluing to the cardboard blank. It is thus easy to print any desired character on the handle blank. It would be almost impossible to print the sides of the handle after it is formed especially where the sides 9th are curved as indicated at 17, Fig. 3.

In this case the element which gives rigidity and strength to the structure considered as a whole is the wire 11. The portion contained within the handle is designed for 100 this purpose and provided with a plurality of corrugations 18 disposed with the hook ends 12 in a vertical plane so as to give maximum strength in the plane of pull on the handle caused by the weighted package 105 which it supports. The blank strip of cardboard is simply wrapped about the corrugated intermediate portion of the wire and

the upper ends 19—20 pressed together to include the upper turns 21 of the corrugations therebetween. The parts are permanently fastened in position, preferably by glue.

5 In the showing in Fig. 4 the handle 22 is intended to represent a material other than the corrugated paper featured in the preceding figures, and may be considered as formed of wood, or preferably a composition, the rigidity of which is enhanced by the presence therein of the corrugated wire shown in dotted outline. The wire insert may be embedded in the composition and the handle moulded about the wire, or, in the 10 case of a preformed handle, the wire may be inserted in a slot 23 and secured either by the resiliency of the material or in any other conventional manner.

15 In either case, the wire reinforcement 20 acts with the covering forming the handle grip to provide a rigid structure capable of withstanding the distorting strains to which such articles are subjected while in use.

25 In place of the glue fastening as recited for the form shown in Fig. 2, wire staples 24 may be used to secure the ends 19—20 either with or without the gluing. In the form shown in Fig. 4 it is suggested that a pin or tack 25 may be used to secure the 30 sides on opposite sides of the slot 23. In both cases the fasteners 24 or 25 function to prevent accidental displacement of the wire 18 and preferably extend between a pair of adjacent bends 26 of the wire. It is particularly true of the hand when formed by 35 cardboard illustrated that the structure is light in weight, is cool to the hand and is designed to fit the hand comfortably without necessity of any more shaping operations than simply bending the blank about the wire and pressing the free ends together.

40 While I have shown and described, and have pointed out in the annexed claims, certain novel features of my invention, it will be understood that various omissions, substitutions and changes in the form and details of the device illustrated and in its operation 45 may be made by those skilled in the art without departing from the spirit of the invention.

50 Having thus described my invention, I claim:

1. A package carrier comprising a handle portion of sheet material, having a one-piece wire provided with hooked ends and an intermediate body portion positioned within the outlines of the handle portion, said intermediate portion of the wire including laterally extending parts constituting a relatively wide wire reinforcement for the handle and coacting therewith to provide a relatively rigid package carrier.

2. A package carrier comprising a paper handle portion having greater depth than 65 width and having a smooth rounded under-

side, and a vertically disposed metallic reinforcement within the paper handle, said reinforcement provided exteriorly of the handle with hooks.

3. A package carrier comprising a cardboard handle portion and a wire reinforcement positioned within the cardboard portion and disposed in a vertical plane, opposite ends of the wire projecting beyond the handle portion and forming hooks. 70

4. A package carrier comprising a layer of corrugated cardboard substantially U-shape in cross section and having a smooth rounded underside, and a corrugated wire reinforcement therefor positioned within the 75 layer.

5. A package carrier comprising a wire having a corrugated central portion and hooked ends, and a grip forming a hand 80 protecting covering for the underside of the corrugated central portion.

6. A package carrier comprising a handle portion having a rounded bottom and 85 standing sides, a single length of wire extending longitudinally of the handle portion, projecting beyond opposite ends and with its projecting ends forming hooks, the portion of the wire within the outlines of the handle portion formed into a plurality of corrugations disposed in a vertical plane. 90

7. A package carrier including a wire having its ends bent into hook form, a strip of corrugated cardboard encircling the portion of the wire between the hook ends with the corrugations extending lengthwise of the encircled portion of the wire, said cardboard having its outer side smooth and providing a handle having a rounded underside and means for securing together opposite ends of the cardboard strip. 100

8. A package carrier including a wire having its ends bent into hook form, a strip of corrugated cardboard encircling the portion of the wire between the hook ends and providing a handle having a rounded underside, and the upper edges of the cardboard strip glued together. 105

9. A package carrier comprising a wire having hooked ends, a hand grip formed of flexible material covering the under portion 110 of the wire between the hooked ends and having parts extending upwardly therefrom and transversely extending fastening means passing through the hand grip for securing the wire in the grip and for securing together the upwardly extending parts of the flexible grip. 120

10. A package carrier comprising a corrugated wire, a hand grip enclosing said wire and fastening means engaging the grip between adjacent corrugations. 125

Signed at New York in the county of New York and State of New York this fifteenth day of December, A. D. 1926.

GEORGE W. CARVER. 130
